UNITED STATES PATENT OFFICE

2,453,125

VACUUM BREAKER

Charles R. Flint, La Porte, Ind., assignor to The Deluxe Products Corporation, a corporation of Indiana

Application December 1, 1945, Serial No. 632,158

7 Claims. (Cl. 123—97)

1

This invention relates to a vacuum breaker, and more particularly to an automatic vacuum actuated device for breaking a vacuum in the idle well of a carburetor on an internal combustion engine.

The present invention is intended primarily for operation during deceleration of an automotive vehicle. Deceleration refers to the operation during which the engine is operating at a higher rate of speed than its carburetor throttle opening would permit if it were working under its own power. A discussion of this problem will be found in my Patent 2,267,020, issued December 23, 1941. In that patent electrical means is shown for providing an auxiliary controlled flow of air to the idle well of the carburetor during deceleration.

The present invention comprises a mechanical system controlled by the vacuum of the manifold itself for operating such an auxiliary flow of air and for maintaining it after the vacuum has fallen due to the admission of the auxiliary air. The present invention also produces an auxiliary flow of air to the manifold which furnishes fresh air thereto during operation of the device.

In its preferred form the control mechanism comprises a vacuum actuated piston having an auxiliary booster chamber which is under vacuum only after actuation of the primary valve.

The invention is illustrated in the drawings in which,

Fig. 1 is a fragmentary sectional elevation; and

Fig. 2 is a section taken along the line 2—2 in Fig. 1.

The device is operated in connection with an automotive engine of any form, which is not illustrated. The device is mounted adjacent the intake manifold 10 of such an engine, adjacent the carburetor 11. The carburetor is of any suitable form and has a conventional idle well opening 12. An auxiliary opening 13 is provided which provides a communication between the chamber 14 and the idle well. A vent 15 is provided from this chamber to the atmosphere. The chamber 14 is closed by the housing 16 which is divided by the diaphragm 17 into chamber 14 and outer chamber 18. The diaphragm is normally pressed by the spring 19 against a needle valve 20 which normally closes the passageway 13.

Chamber 18 is connected by the line 25 to the booster chamber 26.

The actuating mechanism for the needle valve 20 is the valve 30. This comprises a neck 31 suitably attached to and communicating with the manifold 10. The neck communicates with the primary vacuum chamber 32 which is normally

2

closed by the disk valve 33 which seats on the valve seat 34. The disk 33 is preferably of regular polygonal shape with rounded corners as shown in Fig. 2. A disk of this shape is self centering and at the same time provides channels 35 for the passage of air around the disk.

The disk is mounted on the plunger 36 and is normally pressed against the valve seat by a spring 37. The plunger 36 passes through the booster or secondary vacuum chamber 26 and at its upper end carries the booster valve 40 which is of substantially greater diameter than the opening 38 in the valve seat 34. The disk 40 is preferably square with rounded corners like disk 33. Immediately above the disk 40 is an opening 42 having a depending lower edge which forms a valve seat 43. The disk 40, however, does not seat itself upon this valve seat, but there is a small clearance, preferably about .001" when the valve disk is at its uppermost position. A stop 44 prevents the valve from opening too far. The opening 42 communicates with the atmosphere in any suitable manner, preferably through a filter 45.

25 The strength of the spring 37, and the size of the valve openings are adjusted so that the device will operate at the desired vacuums within the manifold. Preferably the device is set to operate whenever the vacuum in the manifold exceeds 21½" of mercury. During the time that the valve is closed spring 37 must offset the pressure upon the opening 38 as compared with the vacuum within the primary valve chamber 32. During this time the secondary valve chamber 26 is under atmospheric pressure.

Whenever the vacuum rises within valve chamber 32 to such an extent as to cause the valve to open, the pressure within the chamber 32 is raised and if it were not for the effect of atmospheric pressure on the secondary valve disk 40, the valve assembly would immediately close. However, pressure within the secondary valve or booster chamber 26 is likewise reduced as soon as the valve opens because the opening to the atmosphere through the annulus 41 is restricted. Therefore, the pressure of the atmosphere upon the disk 40, which is greater in area than the opening 38, tends to keep the valve open. The area is preferably adjusted so that the valve opening at 21½" of vacuum will not close again until the vacuum in the intake manifold has fallen to 15" of mercury.

50 The creation of a vacuum in the chamber 26 communicates itself to the diaphragm 17 and opens the needle valve 20, thereby permitting

air to enter the idle well of the carburetor so long as the valve 30 is open.

The device may be further improved by providing an opening 50 in the wall of chamber 26, which opening is closed by a valve or pad 51 mounted on a crank arm 52. This arm is connected to the accelerator pedal by any suitable mechanical means, not shown, and is actuated simultaneously with the throttle so that as soon as the throttle is opened slightly the valve 51 likewise opens.

The use of a valve 51 has the advantage that the boosting effect of the chamber 26 is eliminated as soon as the throttle opens. In the absence of a structure such as that as the opening 50 and the valve 51 there are certain conditions under which sudden opening of the throttle will cause a surge in the motor, which surge is eliminated by the use of the valve 51.

The foregoing detailed description has been given for clearness and understanding only, and no unnecessary limitations should be understood therefrom.

What I claim as new and desire to secure by Letters Patent is:

1. In the combination including an automotive vehicle having an internal combustion motor, means comprising a carburetor, an intake manifold connected to the carburetor, a throttle valve between the carburetor and intake manifold, a vent communicating with the carburetor, a closure for said vent, means normally actuating said closure into closed position, vacuum means for opening said closure, said vacuum means including a vacuum booster chamber connected to the intake manifold through a valve seat, a valve normally closing said seat, resilient means urging said valve upon said seat, and a secondary valve providing restricted communication between said booster chamber and the atmosphere and rigidly connected to said first valve.

2. Apparatus as set forth in claim 1 in which the secondary valve has a closure area much greater than the closure area of the said valve seat.

3. Actuating mechanism for the relief of vacuum in the carburetor of an internal combustion engine having an intake manifold comprising a primary vacuum chamber in open communication with the manifold, an opening in said chamber, a closure for said opening, resilient means normally urging said closure against said opening, a secondary vacuum chamber in communication with said primary vacuum chamber through said opening, a secondary closure providing restricted communication between said secondary vacuum chamber and the atmosphere, said secondary closure being mounted in spaced relationship to the first closure, and a diaphragm valve communicating with said secondary vacuum chamber and said carburetor.

4. A bleed device for the intake manifold of

an internal combustion engine comprising a primary vacuum chamber in open communication with the manifold, an opening in said chamber, a closure for said opening, resilient means normally urging said closure against said opening, a secondary vacuum chamber in communication with said primary vacuum chamber through said opening, a secondary closure providing restricted communication between said secondary vacuum chamber and the atmosphere, and said secondary closure being mounted in spaced relationship to the first closure, said first closure and said secondary closure being connected for simultaneous movement.

5. A bleed mechanism as set forth in claim 4 in which the engine has a carburetor provided with a throttle and in which the secondary vacuum chamber is provided with an opening, a valve normally closing said opening, and means operating synchronously with the opening of the throttle for opening said valve.

6. A bleed mechanism as set forth in claim 3 in which the engine has a carburetor provided with a throttle and in which the secondary vacuum chamber is provided with an opening, a valve normally closing said opening, and means operating synchronously with the opening of the throttle for opening said valve.

7. In combination with an internal combustion motor, a carburetor, an intake manifold connected to the carburetor, a throttle valve between the carburetor and the manifold, a vent into the fuel passage of the carburetor, means including a diaphragm normally closing the vent, means for applying the vacuum of the intake manifold to said diaphragm when said vacuum is above a predetermined limit, and means actuated by the preceding means for maintaining said preceding means in operation until the vacuum has fallen to a lower predetermined value, said means for applying vacuum to the diaphragm and the last-named means comprise a primary valve seat communicating with the manifold, a valve normally closing the seat, a booster chamber communicating with said primary valve seat and with the diaphragm, and a secondary valve providing a restricted communication from the booster chamber to the atmosphere.
